UNITED STATES PATENT OFFICE.

MORITZ ALBERT ANKELE, OF NEWARK, OHIO.

POULTRY-BROODER.

1,308,470.

Specification of Letters Patent.

Patented July 1, 1919.

Application filed October 3, 1918. Serial No. 256,710.

To all whom it may concern:

Be it known that I, MORITZ ALBERT ANKELE, a citizen of the United States, residing at Newark, in the county of Licking 5 and State of Ohio, have invented a new and useful Poultry-Brooder, of which the following is a specification:

The device forming the subject of this application is a poultry brooder, and one 10 object of the invention is to provide novel means whereby superposed compartments in a brooder may be heated to different degrees, it being possible to move the chickens from one compartment to another, until 15 finally, the chickens are located in a compartment the temperature of which approximates the temperature of the atmosphere.

Another object of the invention is to provide novel means whereby the members 20 which regulate the temperature in the various compartments may be adjusted with respect to said compartments.

It is within the province of the disclosure to improve generally and to enhance the 25 utility of devices of that type to which the present invention appertains.

With the above and other objects in view, which will appear as the description proceeds, the invention resides in the combination 30 and arrangement of parts and in the details of construction hereinafter described and claimed, it being understood that, within the scope of what is claimed, changes in the precise embodiment of the invention can 35 be made without departing from the spirit of the invention.

In the accompanying drawings:—

Figure 1 shows in vertical section, a device constructed in accordance with the invention, parts being left in elevation, and Fig. 2 is a top plan wherein parts are broken away and sectioned.

In carrying out the invention, there is provided a support 1, which may be in the 45 form of an open metal frame provided at its upper end with right angle bends 5. The brooder includes any desired number of superposed annular compartments 6, 7, 8 and 9. The lower compartment includes an 50 outer wall 10 which may be made of netting, the lower edge of the wall 10 being connected to a bottom ring 11 which may be an angle member, the bottom ring being supported removably on the upper end of 55 the frame 1, within the bend 5. The floor 12 of the compartment 6 is supported at its

outer edge on the ring 11, as shown in Fig. 1. The wall 10 is connected at its upper edge to the top ring 14, offset to form a shoulder 15. On this shoulder 15, the compartment 7 and the bottom ring of the said compartment are supported, the compartments 7, 8 and 9 being like the compartment 6, saving for the fact that the top ring 16 of the uppermost compartment 9 carries a netting closure 17. The compartments 6, 7, 8 and 9 are supplied with doors 18. Sleeves 19, which may be made of netting, are interposed between the floors 12 of the various compartments, and between the floor of the 70 uppermost compartment 9 and the top of the closure 17.

A flue 20 is secured at 100 to the support 1 and extends upwardly through the various compartments 6, 7, 8 and 9, it being obvious 75 that the construction is such that the compartments may be lifted readily off the flue. The flue 20 carries a ring 35 which upholds the bottom of the lowermost compartment 6, and, in combination with the sleeves 19, 80 supports the bottoms of the compartments 6, 7 and 8. Asbestos furring strips 21 are interposed between the outer surface of the flue 20 and the inner surfaces of the sleeves 19. The sleeves 19, obviously, form the inner walls of the annular compartments 6, 85 7, 8 and 9. The flue 20 is supplied with longitudinal internal ribs 22.

A heating means of any desired sort is provided, the same in the present instance 90 embodying a fuel supply pipe 23 carrying a burner 24 located within the flue 20 at the lower end thereof. A bracket 26 is mounted on the upper end of the flue 20 and carries a boss 27 through which a rod 29 is mounted 95 to reciprocate for adjustment, the rod extending downwardly into the flue 20 and being held in adjusted positions by means of a screw 28 threaded into the boss 27. At its upper end, the rod 29, which constitutes an 100 operating member, is provided with a handle 30. Disposed within the flue 20 are conical deflectors 31, secured as shown at 32 to the rod 29. The deflectors 31 are individual to the various compartments 6, 7, 8 and 9 and 105 may be adjusted with respect to the floors of the compartments, by moving the rod 29 vertically. The deflectors 31 are engaged at their peripheries with ribs 22 of the flue 20, the ribs serving to space the deflectors from 110 the inner surface of the flue, so that air can pass upwardly between the peripheries of

the deflectors and the inner surface of the flue. Since the deflectors 31 engage the ribs 22 slidably, the deflectors and the rod 29 are guided when the parts are raised and lowered. A conical damper 33 coöperates with the upper end of the flue 20 and is mounted at 34 to slide frictionally on the rod 29. When the rod 29 is raised and lowered, the damper 33 will be raised and lowered also, but it is possible to slide the damper on the rod, and owing to the frictional hold which the damper has, at 34, upon the rod, the damper will remain in any position to which it may have been adjusted.

15 In practical operation, cold air enters the lower end of the flue 20 and is heated therein by the burner 24 or its equivalent. The heated air passes upwardly and is carried laterally by the lowermost deflector 31, the air being carried laterally by the superposed deflectors, the flue 20 being heated and the air in the various compartments 6, 7, 8 and 9 being heated by conduction. Since the sleeves 19 are separated by the furring strips 25 21 from the flue 20, the sleeves, which form the walls of the compartments, will not be heated to such extent as to injure the chickens, should they come into contact with the sleeves. It is to be observed that all of the deflectors 21 may be raised and lowered, by sliding the rod 29 in the boss 27, through the instrumentality of the handle 30, the rod and the deflectors being held in adjusted positions by means of the set screw 28. Consequently, the zone adjacent the floor of each compartment may be increased or diminished in width, thus varying the area which is subjected to the action of the heated air, as the air is carried laterally and outwardly 30 by the deflectors 31. It is possible to slide the damper 33 upwardly and downwardly on the rod 29 as above explained, so as to control the draft through the flue. The lowermost compartment 6 is, of course, heated

to the highest degree, the temperature in the 45 compartments 7, 8 and 9 decreasing, step by step, until, in the uppermost compartment 9, the temperature approximates closely, the temperature of the atmosphere, since the compartment 9 has a foraminous closure 17. 50

Having thus described the invention, what is claimed is:—

1. A brooder comprising a flue; superposed compartments about the flue; deflectors in the flue and individual to the compartments; means for raising and lowering the deflectors together; and a source of heat supply at the lower end of the flue. 55

2. A brooder comprising a flue; superposed compartments about the flue; deflectors in the flue and individual to the compartments; means for raising and lowering the deflectors together; a source of heat supply at the lower end of the flue; and a damper operating at the top of the flue, the 60 65 damper being mounted on said means for adjustment with respect to the top of the flue.

3. A brooder comprising a flue having internal longitudinal ribs; superposed compartments about the flue; deflectors in the flue and individual to the compartments, the edges of the deflectors being engaged slidably by the ribs and being spaced thereby 70 75 from the wall of the flue; a raising and lowering means connected with the deflectors; mechanism connected with the raising and lowering means for holding the deflectors in adjusted positions; and a source of heat supply at the lower end of the flue. 80

In testimony that I claim the foregoing as my own, I have hereto affixed my signature in the presence of two witnesses.

MORITZ ALBERT ANKELE.
